United States Patent Office

Des. 192,991

Patented June 5, 1962

192,991

LAPPET WOVEN TEXTILE FABRIC

Paul Goldberger, 460 Park Ave. S., New York, N.Y.

Filed Oct. 20, 1961, Ser. No. 67,175

Term of patent 3½ years

(Cl. D92—1)

The figure is a plan view of a lappet woven textile fabric embodying my new design.

I claim:

The ornamental design for a lappet woven textile fabric, as shown.

References Cited in the file of this patent

Advanced Textile Design by William Watson, © 1913, page 321, FIG. 334.

Lingerie Merchandising, Part 2, Hosiery and Underwear Review, January 1959, page 83, fabrics, upper right corner.

Lingerie Merchandising August 1955, page 106, bottom, fabric in panel at right center of page.

Lingerie Merchandising, March 1957, page 59, fabric, bottom center of page.